DOOR INTERLOCK

William C. Files, Cincinnati, Ohio, assignor to McGraw-Edison Company, Elgin, Ill., a corporation of Delaware

Filed Sept. 18, 1962, Ser. No. 224,422

14 Claims. (Cl. 200—61.64)

This invention relates to novel and improved safety interlock means for the door or doors of a rotatable cylinder for laundry machines such as washers or extractors.

As is known to those skilled in this art a conventional commercial washer includes a fixed housing usually termed a tub, within which a work container or cylinder is rotatable on a shaft. The shaft end is journalled in bearings in the tub end walls, and one end of the shaft extends outwardly and is driven by power means located on or near the tub.

The tub and the cylinder are provided with respective doors which are registerable for work loading and unloading. After a washing, rinsing and possibly extracting operation the cylinder is stopped; the tub door or doors are opened; the cylinder door or doors are automatically or manually registered with the tub doors; the cylinder doors are opened and the washed charge is unloaded; a new charge is loaded and the cylinder doors are closed and locked; the tub doors are closed and a new cycle commences.

The tub contains processing liquid such as detergent, rinse water, etc., the liquid level being below the lower edge of the tub door. The liquid has access to the charge in the cylinder through apertures in the cylinder walls. A cylinder may have more than one compartment, and in the embodiment herein later described and shown there are two compartments separated by a horizontal diametrical partition. Each compartment of course has its respective door or doors. In loading, the doors of one cylinder compartment are opened, the load inserted, and the doors are closed. The cylinder is then rotated through 180° and the operation is repeated with the other compartment.

Several cylinders may sometimes be placed in end-to-end juxtaposition, in the interest of space conservation or because they can be driven from the same motor, using the same control console or panel, and in the following drawings I show two such cylinders. It is to be understood however that the invention is individually adaptable to a single cylinder.

Since the present invention will be described in its adaptation to the latching and locking means for a rotatable cylinder door, the door for the tub will not be shown, and can be any suitable design, conventional or otherwise.

An object of the present invention is to provide novel and improved cylinder door latching and locking means.

A further object of the invention is to provide, in combination with the latching and locking means mentioned in the last preceding paragraph, means insuring efficient safety features which prevent rotation of the cylinder until its door or doors are closed and locked.

Other objects and advantages will be apparent from a study of the following description of one embodiment of the invention, in conjunction with the accompanying drawings, in which:

FIG. 1 is a perspective view as seen from the right front corner, showing a washing machine assembly embodying my invention;

FIG. 2 is an enlarged fragmentary perspective view of a portion of FIG. 1, but with the cylinder doors closed and locked;

FIG. 3 is an elevational view of a fragmentary detail portion of a cylinder door locking device as shown in FIG. 2;

2

FIGS. 4 and 5 are sectional views taken respectively on the lines 4—4 and 5—5 of FIG. 2;

FIG. 6 is a sectional view taken on the line 6—6 of FIG. 5;

FIGS. 7 and 8 are sectional views taken respectively on the lines 7—7 and 8—8 of FIG. 4;

FIG. 9 is a sectional view, greatly enlarged, taken on the line 9—9 of FIG. 1;

FIG. 10 is a view, similar to FIG. 9, but showing some parts in a different operating position;

FIG. 11 is an end elevational view as seen mainly from the position of the line 11—11 of FIG. 10.

Referring first to FIG. 1, there is shown a laundry unit comprising two cylinders designated generally by the arrows 20 and 21. They are disposed in end-to-end relationship, and are identical in substantially all respects. This is found to be an efficient arrangement from the standpoint of floor space conservation, a common motor drive, a common control panel, common water and supply feed lines, etc. The invention can be adequately shown and described in connection with one cylinder, and in this description and the drawings reference will be made only to cylinder 20.

This cylinder 20 is supported for rotation in a fixed tub, of which we show the supporting end heads 22 and 23. The cylinder is divided into two generally semi-cylindrical compartments by a partition 24. Each such compartment has a door opening which can be closed by two co-operating curved doors 25 and 26 which in the position of FIG. 1 are respectively hinged on opposite upper and lower edges of the opening. In closing they swing to edge abutment, as shown for example in FIGS. 2 and 7. For loading and unloading the compartment shown as accessible in FIG. 1 the cylinder can be rotated so that partition 24 tilts downwardly and outwardly for unloading, or slightly upwardly but inwardly for mechanical loading. The tub door opening is large enough to permit necessary leeway in cylinder swing for these operations. The central drive shaft in housing 27 is driven by a belt 28 from a motor and gear reduction assembly 29, this arrangement being conventional.

Proceeding now to FIG. 2 and subsequent figures, each door part is provided with two oppositely movable latch bolts which, when in latching position, are movably carried on the door and can be advanced to a seat in a retainer in the door jamb. FIG. 4 shows one such bolt 32 movable in a trough or well in the door, its tip end being seatable in a retainer 33. The mid portion of the bolt slides in an aperture in a guide block carried on the door. The apertures in the guide block and retainer come into registry when the door is in closed position.

The bolt 32 is operated by a toggle arrangement comprising an actuator lever or handle 34 which is pivoted at 35 to the bolt, and at a spaced point is pivoted to a pilot link 37 which carries a sleeved extension 37a serving as a socket for a plunger 38. The plunger has an extension 38a which positions a compression spring 39 in the socket. The rear end of the plunger is pivoted at 40 on a pin extending across the well in which the bolt operates. It will be noted that movement of the operating lever between the full line position and the broken line position of FIG. 4 provides an over-center snap-action operation wherein the pivot 36 moves across the line connecting the pivots 35 and 40. The spring 39 provides a bias urging the linkage away from the said center line, both in the direction of bolt advance for latching and bolt withdrawal for unlatching.

FIG. 2 shows four latch handles or levers 34, 34a, 34b and 34c for four respective bolts of the type just described. They are nested in their respective troughs in the four door sections, and in door locked position the

handles are approximately in the plane of the peripheral cylinder door wall 25 (FIGS. 2 and 4). The trough or well previously referred to has a lower level 44 enclosed by the door wall 25. This partition is slotted at 46 to permit operation of the handle 34. The latch bolt 32 and toggle mechanism are in the trough portion 44 and the handle 34 and further associated mechanism are above door wall 25. The roller 47, mounted at the end of trough 44, serves as a fulcrum for the inclined end of handle 34 in exerting force to withdraw the bolt 32.

The purpose of further associated mechanism is to retain the latch handles 34, 34a, etc., in latching position and therefore provide a positive lock. This prevents the handles from flying outwardly under the influence of centrifugal force when the cylinder is rotating. The means just mentioned also prevents energization of the driving motor until after the doors are securely latched and locked, as will appear.

I have provided a clamping bar 48 which is slideable over the ends of a pair of latch handles to hold them in door latched position. It includes a transverse portion 48 and two ends 49 and 50 which have toes 51 and 52 slideable under retaining clips 53 and 54, the clips being welded or otherwise fixed to the respective cylinder door walls 25 and 26. Clip 53 is longer than clip 54 so that movement of clamping bar 48 to clear the handle ends will also clear toe 52 from clamp 54 while retaining toe 51 under clip 53. This permits the doors 25 and 26 to be opened and closed when the clamping bar 48 clears from under clip 54. Clamping bar 48 by itself has the function of a latch since, when in position under clips 53, 54, it prevents or opposes opening swing of the door halves.

The opposed clamping bars 48 and 58 (FIG. 2), each of which is capable of locking two handles, are operated by a linkage now to be described. Directing attention to FIGS. 2, 3, and 4 it will be noted that clamping bars 48 and 58 carry locator brackets 59 and 60 of hook-like form having longer legs 59a and 60a, transverse portions 59b and 60b, and shorter legs 59c and 60c. These legs pass through bridged guides 61a, 61c and 62a, 62c which are carried on the respective reinforcing ribs 63, 63a, 64 and 64a on the periphery of the door halves. It can be seen in FIG. 3 that the short legs 59a and 60a have inclined sides 59d and 60d which cooperate with the fixed cam faces 61d, 62d to give a wedged seat for accurately locating the final positions of brackets 59 and 60 when the clamping bars 48 and 58 are moved to their handle-retaining position. The locator bracket on clamp bar carrier 59 also helps to hold the door halves in closed position when the leg 59c is engaged in guide 61c.

Midway between the brackets 59 and 60 the door wall 25 carries a bushing 68 which is bored to receive a rotary stud 69. This stud is stepped to provide a supporting shoulder 69a which rests on the partition 25, and the tip end of the stud 69b is threaded and extends through bushing 68 to permit application of a washer 70 and nut 71. The structure is well shown in FIG. 5. The nut 71 is tightened until it engages a shoulder 69g on the unthreaded portion of the stud, which portion is somewhat longer than the bushing 68, so that the nut can be pulled up tightly and the stud can still be rotated.

This rotary stud 69 has an upper disc portion 69c which has pivotal connections at 72 and 73 respectively with links 74 and 75. These links in turn are pivoted at 76 and 77 to respective brackets 59 and 60 previously described. Obviously, clockwise movement of the rotary stud will swing the links from the position shown in FIG. 2, which is the latched position, to that shown in FIG. 3, which is the unlatched position.

An additional safety feature is shown in FIGS. 3 and 4. It comprises the cross bar 80 which is carried on an extension rod 81 fixed at one end to the clamping bar 48, and at its other end is slidably fitted in a bore 82 in a fixed bracket 83. Referring to FIG. 3 wherein one latch

5 handle 34 is shown in its latching position and the other latch handle 34a is in unlatched (raised) position, it is of course possible to turn the rotary stud 69 and advance clamping bar 48 to the left to clamping position. Handle 34a however is in unlatched position. Handle 34a cannot now be swung down because its pivot pin extension 36 will strike cross bar 80 and the handle will remain up so that it will be apparent to the operator that the clamping bar 48 must be withdrawn to the right (FIG. 3) to permit lowering of handle 34a, after which the clamping bar can be properly moved to a position where it clamps both handles 34 and 34a. FIG. 2 shows the respective clamping bars 48 and 58 in their proper handle-clamping positions.

15 Operation of the clamping linkage will now be described. FIGS. 5 and 6 show a handwheel 85 having a boss 85a to which is attached a key retainer 86 having a finger or key 87 extending therefrom. The key retainer 86 has a depending projection or locator 86a which enters a central bore in the rotary stud 69. As best seen in FIGS. 2, 3 and 6 the rotary stud is slotted at 69d to receive the key 87 whereby, when the handwheel is pushed down to engage the key in the slot, and the wheel is turned, the clamping linkage is operated. For a purpose soon to appear I have provided a fixed locator ring 90 which is carried on door wall 25 by means of bosses 91 and cap screws 92 (FIG. 5). This ring has a slot 90a which permits the downward insertion of the key finger 87 only at this point.

20 30 It may be here stated that the registration of the slot 90a in the locator ring with the slot 69d in the rotary stud occurs only when the clamping bars 48 and 58 have been moved to handle-retaining position so that in this position the handwheel can be removed, and later reinserted for unlocking. When the handwheel is turned to unlock the clamping bars the key 87 has been rotated to underlie the overhang of ring 90, and the handwheel remains in place as long as the clamping bars remain unlocked. As shown in FIG. 1, the handwheels 85 are retained on and carried with the open doors.

35 40 FIG. 5 shows ejector mechanism which serves a double purpose. In the first place it induces removal of the handwheel and key-retainer assembly when the door has been locked as above described by turning the handwheel until slots 90a and 69d are brought to registry. At this location the key 87 has come to contact with a plunger 93 which is impelled upwardly by a spring 94 so that it urges the key and handwheel up to a non-operating position, facilitating removal of the handwheel and key assembly. Normally the plunger is held down by the unslotted portion of disc 69. FIGS. 2 and 3 show that disc 69 is cut-out at 69e to permit upward movement of plunger 93. In the second place, and of more importance, when the handwheel is removed the plunger 93 pushes up through the cut-out 69e in disc 69 and thereby locks disc 69 and its connected toggles, etc. This prevents accidental reverse rotation of disc 69 from jarring or vibration during cylinder rotation.

45 55 60 With the apparatus so far described, therefore, after both compartments of FIG. 1 have been loaded the doors 25 and 26 are closed, the several latch handles are moved down to insert respective bolts in their retainers, the handwheels carried in the doors are turned to move their respective clamping bars to handle-retaining position, and the wheels can now be removed. They must be removed to permit closing of the outer tub doors.

65 70 75 In the system shown herein the cylinders cannot yet be operated because of additional safety feature now to be described. Considering FIGS. 1 and 11, there are shown certain terminal fragmentary portions of an electric circuit including lines 95 and 96 which are continued to the switch housing 97 in FIG. 11. This could of course be a three-phase circuit with one additional line. The connection to the supply line is indicated at L1, L2 in FIG. 11. The complete electrical circuit need not be

shown since it can easily be supplied with even rudimentary electrical skill. Depression of button 98 operates a micro-switch in housing 97 to energize the motor drive 29 (FIG. 1). Operation of this switch is achieved by means of the handwheel and key assembly already described.

Referring now to FIGS. 1, 9, 10 and 11 I show the handwheel 85, with its key retainer 86 and key 87 using the same reference characteristics as in the previous description and drawings. It is operated as follows. A cuffed housing 100 has side walls 101, 102 and a bottom wall 103. A sleeve 104 is welded in an aperture in the bottom wall. A collar 105 surrounds another aperture in the top wall 106. This cuffed assembly is carried on the front panel 107 of the control console 108, FIG. 1. A depressible bushing 110 is slidable in the sleeve 104 and is biased upwardly by compression spring 111. Upward movement of the bushing 110 is limited by abutment of a collar 112 which abuts the sleeve 104 and which is fixed on bushing 110 by a set screw 113. Collar 112 carries a switch operating finger 116 which can be rotated to a position where it contacts and depresses the switch button 98 hereinabove mentioned.

In operation the handwheel key retainer 86 is inserted through collar 105 which has a slot 117 to permit passage of key 87. The locator pin 86a enters the aperture in bushing 110, and key 87 enters a slot 118 in the upper discoidal portion 110a of the bushing. A segmental undercut 119, of 90 degrees extent, has been machined on the under surface of part 105 having at one radial end the slot 117 and at its other radial end a groove 120. When the handwheel is inserted and depressed against spring 111, the key 87, which has a lower edge portion in slot 118, is rotated along the segmental cut-away 119 until the key reaches the end of its swing and comes to registry with groove 120, at which time spring 111 pushes bushing 110 and causes key 87 to snap into a seat in groove 120. At this point (FIG. 10) finger 116 depresses button 98 and closes the circuit to the cylinder motor.

To secure proper alignment of the parts the set screw 113 can be loosened until the key 87 is in the opposed grooves 118 and 120 at which time collar 112 can be turned until finger 116 depresses button 98 until the switch is closed, whereupon set screw 113 can be tightened.

Sufficient clearance is provided between bushing 110 and collar 112 to permit the necessary travel of bushing 110, but when the key 87 drops into groove 120 there will be little if any clearance between the sleeve 104 and the collar 112.

To stop the cylinder motor the handwheel is pushed in, depressing plunger 110 until key 87 sufficiently clears groove 120 to permit the key 87 to be radially rotated until it reaches slot 117 in collar 105, after which the wheel can be lifted out completely. The motor stopped, of course, as soon as finger 116 released button 98. The handwheel is now available for use in unlocking the cylinder doors as hereinabove described.

FIGS. 7 and 8 show, in section, certain details not fully characterized hereinabove. The meeting plane of door parts 25 and 26 is shown at P in each figure. The guide blocks 121 and 122 are carried on the respective door edges. FIG. 7 shows the upper door pivot point at the hinge pin 123. Strengthening straps 124 and 125, respectively on the tub and the door and the cylinder, are shown in respective FIGS. 8 and 7, and in perspective in FIG. 2 and the horizontal strengthening strap 126 is also shown in FIG. 7 and FIG. 2.

While I have shown a washing arrangement in which two cylinders are operated end-to-end in a unitary set-up, a single-cylinder washer is of course usable for a less extensive operation. It would also be quite feasible to adapt a latching and clamping device, such as I have herein shown, to a cylinder having only a single door instead of the two-part door shown in the figures. Similarly, it

would be quite feasible to have a clamping means which clamps only one latch handle instead of a pair of latch handles simultaneously.

What is claimed is:

- 5 1. In a latching and locking mechanism for a door movable between open and closed positions in a door frame, said mechanism including a latch bolt movably mounted on said door, said frame having a retainer socket in alignment with the path of movement of said bolt so as to receive an end of said bolt in door-latching position, a handle carried on said door, means operatively connecting said handle and said bolt whereby, upon handle swing, said bolt is moved to latched or unlatched positions, clamping means carried on said door and movable to retain said handle when said handle is moved to door-latched position, a rotatable member also carried on said door, a toggle linkage, one end of said toggle linkage being connected to said rotatable member and the other end to said clamping means, and means for rotating said rotatable member whereby said toggle linkage is actuated, and said clamping means is moved to handle-clamping position.
- 10 2. Mechanism as defined in claim 1 wherein said clamping means consists of a clamping bar slidably mounted to permit movement to a position blocking operation of said handle when in door-latched position.
- 15 3. In a latching and locking mechanism for a door movable between open and closed positions in a door frame, said mechanism including a pair of latch bolts mounted on said door to move in opposite directions thereon, said frame having opposed sockets in respectively opposed frame portions, each socket being in alignment with the path of movement of a respective bolt whereby to receive a respective end of the last said bolt in door-latching position, a pair of handles carried on said door, means operatively connecting each said handle and its said bolt whereby, upon swing of said handle, its connected bolt is moved to latched or unlatched position, clamping means carried on said door and movable to retain each said handle when said handle is moved to door-latched position, a rotatable member, a toggle linkage, one end of said linkage being connected to said rotatable member and the other end to said clamping means, and means for rotating said rotatable member whereby said toggle linkage means is actuated, and said clamping means is moved to handle-clamping position.
- 20 4. Mechanism as defined in claim 3 wherein said clamping means is slidably mounted to permit movement to a position blocking operation of said handle when in door-latched position.
- 25 5. Mechanism as defined in claim 1 wherein obstruction means is provided on said clamping means to permit swing of the handle to door-latching position only when said clamping means has been withdrawn to an unclamping position.
- 30 6. Mechanism as defined in claim 1 wherein said rotatable member has a key slot therein, and means for rotating said rotatable member including a manually portable key carrier having an elongated key fitable in said slot, and means on said rotatable member for retaining said key in said slot when the key carrier has been rotated to door-unlatched position.
- 35 7. Mechanism as defined in claim 6 and including ejector means for removing said key from said slot when the key carrier is rotated to door-latched position.
- 40 8. Mechanism as defined in claim 7 wherein said ejector means consists of a spring-impelled plunger biased to exert ejecting pressure against said key.
- 45 9. Latching and locking means for the door of a rotatable cylinder of a motor-operated washing machine, said means including a latch bolt movably mounted on said door, a frame for said door having a retainer socket in alignment with the path of movement of said bolt whereby to receive an end of said bolt when the bolt is moved to door-latching position, a handle carried on said door,
- 50
- 55
- 60
- 65
- 70
- 75

means operatively connecting said handle and said bolt, said handle being swingable to latch and unlatch the bolt, clamping means carried on said door and movable to retain said handle in its door-latched position, electric circuit means adapted, when closed, to energize the motor, a switch in said circuit and a key member removable from a first position to a second position spaced therefrom, and adapted when in said first position, to cause clamping and unclamping of said latch handle and when in said second position to cause closing of said circuit only when said latch handle is in latching position.

10. In a latching and locking mechanism for a door movable between open and closed positions in a door frame said mechanism including a pair of latch bolts mounted on said door to move in opposite directions thereon, said frame having opposed sockets in respectively opposed frame portions, each socket being in alignment with the path of movement of a respective bolt whereby to receive a respective end of the last said bolt in door-latching position, a pair of handles carried on said door, means operatively connecting each said handle and its said bolt whereby, upon swing of said handle, its connected bolt is moved to latched or unlatched position, clamping means carried on said door and movable to retain each said handle when said handle is moved to door-latched position, a rotatable member, a toggle linkage, one end of said linkage being connected to said rotatable member and the other end to said clamping means, and means for rotating said rotatable member whereby said toggle linkage means is actuated, and said clamping means is moved to handle-clamping position, said rotatable member having a key slot therein, means for rotating said rotatable member including a removable key carrier having an elongated key receivable in said slot in a first position whereby by movement of said key carrier said rotatable member is actuated, electric circuit means adapted when closed to energize the motor, a switch in said circuit, receptacle means adjacent said switch to receive said key carrier in a second position spaced from said first position, said key carrier when in said second position being movable to either one of two settings, and adapted, when in one setting, to permit opening of said circuit, and when in the other setting to cause closing of said circuit, said key carrier being removable from said first position only when said clamp is in clamping position.

11. Latching and locking mechanism for a door mov-

able between open and closed position in a door frame including a latch bolt carried on said door and movable to a door-securing position and means for retaining said latch bolt in said door securing position including bolt clamping means carried on said door, a rotatable member also carried on said door and operatively effective on said clamping means to move it to clamping position, a handwheel having a key portion fittable into an aperture in said rotatable member whereby, upon movement of said handwheel, to rotate said rotatable member, a locator member fixed on said door above said rotatable member and having a cut-away slot to admit the said key portion of said handwheel to operative engagement with said rotatable member when this member is in clamping position and to retain said handwheel when the rotatable member is rotated by the handwheel to unclamping position.

12. Mechanism as defined in claim 11 wherein said operative engagement between said rotatable member and said latch bolt is a toggle linkage connected at one end to said bolt and at the other end to said rotatable member.

13. Mechanism as defined in claim 11 wherein a plunger is movably mounted beneath said rotatable member, and spring biased to pass through said aperture and into said slot when the said aperture and said slot come to alignment in bolt clamping position, said plunger being depressible by said key portion of said handwheel when the handwheel and key portion are inserted to move said rotatable portion to unclamping position.

14. Mechanism as defined in claim 2 wherein said door has two parts swingable on respectively opposed hinges to a closed position in which the respective free-swinging edges are in edge abutment, a socket on each door part adapted to receive respectively opposed ends of said clamping bar when the clamping bar is moved to said handle-blocking position, whereby to provide door securing means additional to the clamping of said handle.
